POCKET CIGARETTE ROLLER

Erik Edward Hollander, Kearny, N. J.

Application November 5, 1931, Serial No. 573,099

3 Claims.

(Cl. 131—5)

There are many individuals who for various reasons prefer to prepare their own cigarettes to buying them ready made. Few, however, possess the inborn dexterity required to "roll their own" 5 in a satisfactory manner. The whole operation is a rather complicated one, and also requires the separate storing of cigarette paper, tobacco and paste. Even the few gifted with the faculty of accomplishing results in this respect do not find 10 it any too convenient to produce a cigarette on "the spot" in the minute desired.

My invention will make it possible for any normal person to transform a quantity of tobacco into a cigarette the very minute it is needed and 15 without more effort than that required to use a cigarette lighter.

I will now describe one way of executing the idea of my invention without, however, thereby limiting in any way the total scope and possible 20 variations of the basic idea of my invention.

Fig. 1 shows a partly sectional view of one form of cigarette roller according to my invention, certain parts being broken away in order to reveal the interior structure, as will be explained 25 below. Fig. 2 is a perspective view of the apparatus in opened condition. Fig. 3 is a cross section through the apparatus, taken along line 3—3 in Fig. 1, looking from left to right.

Referring to the drawing, 1 is an outer case or 30 shell. 2 is an inside compartment which is used to store a supply of tobacco. 3 is a subcase having sides 23, bottom 19 and hinged lid 20. This subcase is used to store a supply of cigarette 35 papers. Fig. 1 shows case 1 with the upper side partly broken away on upper and lower left hand corners and on the lower right hand corner. Lid 20 is bent upwardly at its hinged side in the shape 40 of a circular compartment 4 opening interiorly through a slit, and this compartment is used as a paste container. The bending embodies a slight spring action so that the slit is practically closed but does not prevent the entering therethrough of part 7 described below. On lid 20 is also attached the combined paste applicator and 45 paper inserter 7 consisting, in its simplest form, of a metal sheet or plate that can slide forward and backward when manipulated by the springy attachment 8, which is joined thereto by an element that extends through an opening in lid 20.

50 The above mentioned sliding movement of sheet or plate 7 has two objects. If plate 7 is slid in one direction it enters the paste compartment 4 and causes some paste to adhere thereto. When slid in the other direction, plate 7 frees one 55 paper at a time from the grip of the fine paper

studs or prongs 6, and forces this paper into the slit of the circularly bent end 5 of part 23 which contains the combined paper roller and tobacco filler 12, which latter device can be rotated approximately one turn and moved laterally of the case or shell. Filler 12, shown in Fig. 1 with parts broken away, consists of a split tube with crowned or forked portion at its inner end; the tube slidingly operates through a contraction ring 13. Filler 12 is also provided with a retaining arrangement 18 consisting of a piece of metal wire bent into the shape of a hook that will slide laterally in the tubular compartment 5 until it snaps into groove 17. At its exterior end, filler tube 12 is provided with a head or finger piece 15. 10 The crowned or forked inner end portion of filler 12 serves to better grip the tobacco for pushing the latter into a formed paper tube, than would be the case if this portion were plain or blunt.

The operation of rolling a cigarette is performed as follows: After a cigarette paper has been given an edging of paste and moved through the slit of circularly bent portion 5, above described, it is brought in reach for the rolling action of combined roller and filler 12. By twisting or rotating filler 12 approximately one turn, the cigarette paper, guided by the crowned end portion of filler 12 and by the contraction ring 13, is rolled and thus wrapped around filler 12 so that a closed tubular receptacle of paper is formed for the reception of the tobacco. After this, filler 12 is moved longitudinally outward in a lateral direction relative to the case, and is, during this movement, slightly squeezed together by the contraction ring 13, so that the paper is left intact 30 within compartment 5. When filler 12 is thus retracted, a space is left into which tobacco is free to enter through the opening 16 from inside compartment 2, thus lodging some tobacco in front of filler 12, so that, when filler 12 is moved inward, this tobacco is passed through contraction ring 13, which acts like a funnel, and is thereupon pushed into the paper tube. When the paper tube has been filled with tobacco, by repeating the last described operations two or three times, 35 the head or finger piece 15 is pressed all the way in against the case, whereby the completed cigarette is pushed through an opening ordinarily closed by the hinged cap 10.

The apparatus can also be used without the 50 outside casing. A bag containing tobacco is, in such event, tightened around opening 16.

Having described my invention, I claim:—

1. In a device of the kind described, means to provide a tubular compartment having an en- 55

trance slit along its side through which a cigarette paper may be entered, a combined paper roller and tobacco filler in the form of a longitudinally split tubular member adapted to be both 5 rotated and reciprocated in said tubular compartment, a contraction ring at one end of said tubular compartment through which said tubular member moves, and means providing a passage through which modicums of tobacco may be deposited between the retracted tubular member 10 and said contraction ring for the purposes described.

2. In a device of the kind described, means to provide a tubular compartment having an entrance slit along its side through which a cigarette paper may be entered, a combined paper roller and tobacco filler in the form of a longitudinally split tubular member adapted to be both rotated and reciprocated in said tubular 15 compartment, a contraction ring at one end of 20

said tubular compartment through which said tubular member moves, means providing a passage through which modicums of tobacco may be deposited between the retracted tubular member and said contraction ring for the purposes described, and a removable closure means at the opposite end of said tubular compartment adapted to be opened for the ejection of a formed cigarette from the latter. 5

3. In a device of the class described, a casing, 10 a tubular compartment at one end thereof, means for holding cigarette papers in the casing, a paste-holding compartment in the casing, a movable plate mounted in the casing, means for manipulating the plate to apply paste to a cigarette 15 paper and insert said paper in the tubular compartment, a cigarette forming member in the tubular compartment, and means for contracting and withdrawing the cigarette-forming member. 20

ERIK EDWARD HOLLANDER. 20
